UNITED STATES PATENT OFFICE.

WARREN B. WHITE, OF NORTH ABINGTON, MASSACHUSETTS.

COUNTER AND TOE STIFFENER FOR BOOTS AND SHOES.

1,102,113.

Specification of Letters Patent. Patented June 30, 1914.

Application filed February 24, 1914. Serial No. 820,746.

To all whom it may concern:

Be it known that I, WARREN B. WHITE, a citizen of the United States, residing at North Abington, in the county of Plymouth, State of Massachusetts, have invented a certain new and useful Improvement in Counter and Toe Stiffeners for Boots and Shoes, of which the following is a specification, reference being had there-

10 in to the accompanying drawings.

Counter and toe stiffeners such as are employed in the manufacture of boots and shoes usually are made with the flanges and bodies thereof integral with each other. As 15 thus made, the blank for a stiffener requires to have a width equal to the combined width of the upright or body-portion of the stiffener and the horizontal portion or flange. In other words, the blank requires to consist of a comparatively wide piece of material, the cost of which is in proportion to the width, which renders quite large the cost of stiffeners of the better classes made of good and high-priced material. A blank 20 such as aforesaid is taken, and by a molding operation the flange-portion thereof is bent at the required angle to the body-portion, the required general shape being given to the stiffener at the same time. In the 25 said operation the inturned flange of the stiffener is produced by turning or bending the lower integral portion of the blank inwardly, and pressing or ironing the same to give the required set thereto to cause it 30 to stand at or nearly at right angles to the upright body-portion. The angle between the upright body-portion and the flange is defined by the bend in the entire thickness of the material of the blank. The fullness 35 or excess of material in the flange resulting from giving the stiffener the customary horse-shoe shape is formed into crimps, which are flattened down in the pressing or ironing operation. The heel-seat constituted 40 by the inturned flange of a counter-stiffener, for instance, should be flat, and a sharply-defined angular bend with flat base line are 45 highly desirable. These features are difficult to produce in the case of a one-piece 50 stiffener shaped wholly by molding, and inasmuch as the leather or other material of which stiffeners are made, when bent to form an angle, shows a tendency to flatten down or straighten out again so as to lose 55 the required angle, especially in case of

being moistened, a well-defined angular bend and the requisite flatness of the crimped heel-seat do not always remain. If a molded stiffener becomes damp or jammed the corner or bend loses its well-defined sharpness or angularity and becomes rounded, and the flange tends to straighten out into line with the upright portion. Consequently, neither a good heel-seat, a well-defined angular bend and distinct base-line, nor a satisfactory outer side, remains. When the flange departs from the desired degree of angular relationship to the upright body-portion, the flange will not fit well against the heel-seat of a last. 60 Hence, in the lasting process it frequently becomes necessary to flatten the heel-seat of a counter-stiffener by pounding, and also to square up the outer side of the stiffener by beating with an iron. In some cases, 65 stiffeners molded as aforesaid are wet or moistened for the purpose of putting them in temper, to thereby facilitate working the flange of a stiffener into place upon a last. 70 When thus wet or moistened, the stiffener 75 partially loses the shape which was given to it in the molding operation, so that the shoulder or bend produced by molding disappears more or less completely, and the latter then has to depend largely upon his 80 eye in bending or breaking the flange around the edge of the last and into place for the heel-seat of a shoe. In so doing, it is difficult for him to bend or break the 85 stiffener with such accuracy that in the finished shoe the upper edge of the stiffener 90 shall stand at exactly the right height, and hence it results frequently that the top edge of a stiffener stands too high or too low in the finished shoe. A departure of even so 95 small an amount as one-eighth of an inch from the correct position injures a shoe.

One general object of the invention is to provide for securing a perfectly-defined base-line for a stiffener, and a clearly-defined external corner at such base-line, and also to provide for a perfect flange or heel-seat extending inward at the proper angle from the body-portion. These are things that cannot be attained, or at any rate are 100 difficult to attain, when the flange or heel-seat is integral with the body-portion and produced simply by imparting a bend or set to the lower portion of a blank. By attaining this and the related objects of the invention 105

- tion I provide, for instance in the case of a counter-stiffener, for a snug fit of the flange of such stiffener against the heel-seat of a last, and also for the desired appearance of the shoe around the lower part of the counter next the sole. The laster is enabled to keep the heel-seat of the stiffener close to the last, pounding is rendered more or less completely unnecessary, and time is saved.
- 10 A second general object of the invention is to produce a stiffener which will stand being wetted or moistened without losing the angle of the heel-seat or the square corner, and thereby obviate bending of the stiffener by the laster to form a flange.
- 15 A third general object of the invention is to provide for a more advantageous use of material; also to provide for enabling stiffeners to be made of smaller pieces of material, and for enabling the flanges to be made of less expensive material than that of which the bodies are formed.
- 20 A fourth object of the invention is to obviate the skiving of the lower portion of a stiffener heretofore necessary to facilitate the bending of such portion to form a flange or heel-seat, and by dispensing with such skiving enable the full original substance and thickness of the body to the lower edge of the latter to be retained.
- 25 A fifth object of the invention is to insure uniformity of height from the heel-seat up, of the counter-stiffeners in the different shoes of a lot.
- 30 A sixth object of the invention is to facilitate the operation of uniting the body-portion and flange-portion, when composed of separate pieces, and thereby expediting the process of manufacture and reducing the cost.
- 35 Briefly stated, the invention consists in a stiffener for use in the manufacture of boots and shoes in which the body and the flange respectively consist of separate pieces of material secured together by fastening means, the cut edge of one of such pieces adapted to define the base-line of the stiffener and to give an angular corner at such base-line.
- 40 It consists, further, in a stiffener for use in the manufacture of boots and shoes comprising a body-portion and a flange-portion secured together, flat face of one to flat face of the other, with one of said portions adapted
- 45 to be bent to thereby cause the flange to occupy a position substantially at right angles to the upright portion, and with the cut edge of one thereof adapted to define the angle at the base of the stiffener and also define the heel-seat.
- 50 Any suitable means of fastening the different portions of the stiffener together consistent with the aims of the invention may be employed in practice, although as one of
- 55 the more specific features of the invention I

employ stitches in some instances. In others, I employ wire fastenings. In still others I employ cement.

The invention is applicable equally in the case of counter-stiffeners and of toe-stiffeners, although for convenience I have referred more particularly herein to counter-stiffeners, and have shown the features of invention embodied in counter-stiffeners. The embodiment of the said features in toe-stiffeners will be obvious to those skilled in the art.

In the drawings,—Figure 1 is a view of the outer side of a counter-stiffener containing one embodiment of the invention, said counter-stiffener being shown in flat unmolded state. Fig. 2 is a view of the inner side thereof. Fig. 3 is a view in vertical cross-section of a counter-stiffener containing the said embodiment, molded into shape for application to a shoe, and having the lower portion of its flange-piece bent into horizontal position to constitute a flange. Fig. 4 is a view similar to Fig. 3 but showing both portions of the flange-piece bent to constitute a flange. Figs. 5 and 6 are views similar to Figs. 1 and 2, showing a second embodiment of the invention. Fig. 7 is a view in vertical cross-section of the counter-stiffener of Figs. 5 and 6, and Fig. 8 is a similar view thereof showing it after the flange has been bent into horizontal position. Figs. 9 and 10 are views similar to Figs. 1 and 2, showing a third embodiment of the invention. Fig. 11 is a view in vertical cross-section of the body-piece of the counter-stiffener of Figs. 9 and 10. Fig. 12 is a similar view of the said counter-stiffener after the flange-piece has been united to the body-piece. Fig. 13 is a view in vertical cross-section of a counter-stiffener containing the said third embodiment of the invention, showing the flange bent into horizontal position.

Having reference to the drawings, and more particularly to Figs. 1 to 4,—the body-piece 1 usually is composed of leather, although in some cases I use leather-board or like material. Its width corresponds with the height of the body-portion of the finished counter, its upper margin being skived as usual, while its lower portion presents a square-cut edge. The flange-piece 2 is composed of a suitable flexible material. This material may be canvas, or it may be thin leather stock. The flange-piece is applied to one surface of the body-piece and united thereto. Herein it is shown applied to the inner surface of the body-piece. The uniting means may vary in practice, but usually I employ a line of fastenings 3, as shown, located adjacent the lower edge of the body-piece and preferably consisting of stitches. The body-piece and the flange-piece are placed together face to face, and the stitches

3 pass through the two thicknesses. The flange-piece is shown in these figures as of a width twice that of the flange of the finished stiffener, and attached to the lower 5 margin of the body-piece at about the middle of the width of the flange-piece. In Fig. 3 the upper portion of the flange-piece remains in upright position in contact with the inner surface of the body-piece, to which 10 surface it is caused to adhere by means of a suitable cement or adhesive, although this may be dispensed with, while the lower portion is bent to form the instanding flange. As cemented to the body-piece in Fig. 3, the 15 upper portion of the flange-piece 2 forms an effective reinforcement for the said body-piece, taking the place of the separate reinforcement which sometimes it is found necessary to apply in practice. When the 20 flange-piece is caused to adhere to the body-piece by cement or the like, the line of stitches or other fastenings may be omitted. However, the line of stitches has its advantages. For instance, in Fig. 3 it prevents 25 the flange-piece from tearing away from the surface to which it is cemented. Where the flange is composed of a single thickness the total width of the flange-piece may be less than that indicated in Figs. 1 to 4. In Fig. 30 4 the upper and lower portions of the flange-piece are bent horizontally and brought together so that they combine to form the flange. Inasmuch as the vertical width of the body-piece determines the height of the 35 stiffener, this insures uniformity in the height of the different stiffeners of a lot when applied to the shoes in which they are incorporated.

In Figs. 1 to 4 the lower cut edge of the 40 body-piece 1 defines the base-line of the body of the stiffener and gives a sharply-defined angle. The full original substance and thickness of the said body-piece is retained at the said edge. I may, however, reduce the said 45 thickness more or less at the said edge in cases when such reduction is deemed advisable or necessary.

Figs. 5 to 8 show an embodiment of the invention in which the angle and base-line 50 at the bottom of the body of the stiffener are defined by the cut edge of the flange-piece. In this embodiment of the invention the body-piece 1^a has both the upper margin and the lower margin of the same skived or 55 tapered in thickness. The flange-piece 2^a is applied to the outer surface of the lower margin of the body-piece 1^a. The upper margin of the flange-piece overlaps the lower margin of the body-piece a short distance, 60 the extent of the overlapping being sufficient to provide for the secure attachment of the two pieces to each other by the line of stitches or other fastenings 3^a. In shaping the stiffener for application to a shoe, a bend 65 is produced in the lower margin of the body-

piece 1^a, closely adjacent the line of stitches or other fastenings 3^a, as shown by Fig. 8, so that the outer edge of the flange-piece in the horizontal position of the latter represented in Fig. 8 shall be flush, or approximately so, with the upstanding portion of the outer surface of the body of the stiffener. In this embodiment of the invention the flange-piece may be composed of stock sufficiently thin not to require skiving to 70 produce a satisfactory heel-seat, or if thicker and less flexible material is used for the flange-piece the latter may be skived. 75

Figs. 9 to 13 show an embodiment of the invention in which the lower margin of the body-piece 1^a, instead of being skived as in Figs. 5 to 8, may be simply reduced in thickness, as by means of a knife or knives or a rotating cutter, producing a thin lip 1^c and a longitudinal shoulder 1^d. In this case the 80 flange-piece 2^b is applied to the outer surface of the body-piece 1^b substantially as in Figs. 5 to 8, and the line of stitches or other fastenings 3^b passes through the upper margin of the flange-piece 2^b and the lip 1^c. In 85 shaping the stiffener for application to a shoe the flange is caused to occupy a horizontal position projecting inwardly by bending the lip 1^c inward and up against the shoulder 1^d as in Fig. 13. In the case of 90 this embodiment also, the outer cut edge of the flange-piece defines the base-line of the body of the counter, and the angle at the base of the said body. The flange-piece of 95 this embodiment may be composed of thin 100 flexible unskived material or stock, or may be skived as shown in Figs. 12 and 13 if preferred.

The operation of uniting a body-piece and a flange-piece laid together face to face, by 105 means of stitches passing through and through from the top surface of the one to the bottom surface of the other, is very conveniently and rapidly performed with the aid of suitable stitching mechanism and 110 guides, so that the cost of manufacture is small. The body-piece may be composed of one or a plurality of thicknesses, and in some cases the strip constituting the flange-piece may be confined between two body 115 layers. By making the body-piece of a width no greater than the height of the counter, I am enabled to effect an economy in the use of the comparatively high-priced material ordinarily used in the manufacture 120 of counter-stiffeners, through being able to employ a smaller piece of such material and lower priced material for the flange. In the case of the embodiment shown in Figs. 5 to 13, I employ as the flange-piece the strip 125 that is skived off from the upper margin of the body-piece in preparing the latter.

My invention enables me to reduce the cost of manufacture by effecting a saving in the cost of material and in labor, and 130

through manufacturing the stiffeners at a more rapid rate of production.

When the flange-piece is stitched to the inner face of the body-piece and turned down as in Figs. 1 to 5, the downwardly projecting margin of the body, below the attaching seam and the bend of the flange-piece, accommodates the bulk of the crimped portion of the upper of a shoe, and the backstay when the latter is employed in the shoe, permitting the lower edge of the body of the counter and the upper inclosing the same to fit more snugly against the outsole of the shoe.

15 My invention provides for the production of a stiffener having a stiff upright body adapted to be conveniently shaped and to retain the shape which has been given thereto, and a flexible flange which can readily be worked into position in a shoe and secured in such position in the latter.

Stiffeners embodying my invention may be fully shaped in readiness for being fitted to a last before being placed upon the market, or may be sold in a flat state or in a more or less open and straight condition, slightly concaved transversely and slightly curved longitudinally in readiness for being given their final shape by the laster just previous to applying them to a last.

I claim as my invention,—

1. A stiffener for use in the manufacture of boots and shoes comprising an upright body-portion of a vertical width corresponding with the height of the stiffener, and having an edge defining the base-line of said body-portion and a separate flange-portion secured to the said upright body-portion and bent inward at the lower edge of the said body-portion to constitute a flange.

2. A stiffener for use in the manufacture of boots and shoes comprising an upright body-portion and a flange-portion, secured together flat face to flat face, with one of said portions bent to cause the flange to occupy a position approximately at right angles to the upright portion, and with one portion provided with an edge defining the base-line of the stiffener and the angle at the base of the stiffener.

3. A stiffener for use in the manufacture of boots and shoes comprising a body-portion and a flange-portion, contacting flat face to flat face and stitched together through and through, with the flange standing inward at an angle from the body-portion in the stiffener as ready for use and with an edge of one of said portions defining the base-line of the stiffener and the angle at the base of the stiffener.

4. A stiffener for use in the manufacture of boots and shoes comprising a body-portion and a flange-portion united together flat face to flat face, one of said portions having an edge arranged to define the base-line and angle at the base of the stiffener when the stiffener is bent into shape for use.

5. A stiffener blank for use in the manufacture of boots and shoes comprising a body-piece and a distinct flange-piece secured together, flat face of the one to flat face of the other, with one of said pieces arranged to be bent to thereby position the flange at an angle to the body, and with the edge of one thereof arranged to define the angle at the base of the stiffener and also define the heel-seat.

6. A stiffener for use in the manufacture of boots and shoes comprising an upright body-portion and a flange-portion cemented together flat face to flat face, whereby said flange-portion constitutes a reinforcement for the body-portion, said body-portion having an edge which defines the base line of the stiffener and serves to give an angular corner at such base line.

7. A stiffener for use in the manufacture of boots and shoes comprising an upright body-portion and a flange-portion cemented together flat face to flat face, whereby said flange-portion constitutes a reinforcement for the body-portion, said body-portion having an edge which defines the base line of the stiffener and serves to give an angular corner at such base line, and a line of stitches extending lengthwise of said edge and further attaching said parts of the stiffener together.

In testimony whereof I affix my signature in presence of two witnesses.

WARREN B. WHITE.
